COMBINED CARRIAGE AND CAGE FOR BIRDS

Samuel P. Benjamin, Jr., New York, N.Y., assignor to
Donald C. Benjamin, doing business as Holland Amer-
ica Carriage & Import Company, New York, N.Y.

Application June 3, 1958, Serial No. 51,167

Term of patent 14 years

(Cl. D31—2)

FIG. 1

FIG. 3

FIG. 2

FIG. 4

Fig. 1 is a perspective view of a combined carriage and cage for birds showing my new design;

Fig. 2 is a left side elevational view thereof on a reduced scale, the right side being substantially like the left side shown;

Fig. 3 is a front elevational view thereof on a reduced scale; and

Fig. 4 is a rear elevational view thereof, on a reduced scale.

I claim:

The ornamental design for a combined carriage and cage for birds, substantially as shown and described.
